UNITED STATES PATENT OFFICE.

JAMES EDWIN PETTIBONE, OF ST. LOUIS, MISSOURI.

FILM-PACK.

1,081,770.

Specification of Letters Patent.

Patented Dec. 16, 1913.

Application filed October 22, 1912. Serial No. 727,165.

To all whom it may concern:

Be it known that I, JAMES EDWIN PETTIBONE, a citizen of the United States, and a resident of St. Louis and State of Missouri, have invented certain new and useful Improvements in Film - Packs, of which the following is a specification.

My invention is an improvement in film packs, and has for its object the provision 10 of a pack of the character specified of great simplicity, convenient of manipulation, wherein the films are attached to a continuous strip so arranged that at no time during the manipulation of the films is there more 15 than a single tab exposed, wherein the moving of each film from exposed position uncovers the succeeding film, the strip to which the films are attached being so folded that each fold when pulled straight, will move 20 the film attached from the front to the rear.

A further object of the invention is to arrange the strip, so that each fold of the paper when drawn away, may be torn off, leaving a tab to move the next film from the 25 front to the rear.

In the drawings:—Figure 1 is a perspective view of the pack before use, Fig. 2 is a similar view of a part of the pack with the safety cover withdrawn, Fig. 3 is a perspective view of the metal support, Fig. 4 is a perspective view of the supporting frame for the opening of the pack, Figs. 5 and 6 are sections on the lines 5—5 and 6—6 respectively of Fig. 3, Fig. 7 is a central vertical section through the pack, Fig. 8 is a horizontal section, Figs. 9 and 10 are enlarged vertical longitudinal sections showing different positions of the parts during the manipulation of the pack, and Fig. 11 is 40 a perspective view of a portion of the supporting strip showing the method in which the films are attached.

The present embodiment of the invention comprises a case formed from a single piece 45 of suitable material, as for instance, light card-board, having its side edges and ends flanged laterally and then doubled upon itself transversely to form the case 1, the side flanges lapping upon each other and 50 being secured together as are also the end flanges. The end that connects the front and the back of the case is provided with a slot 2, through which the tabs for moving the film extend, and the front of the 55 case is cut away to form an opening 3 for exposing the films.

The metal support consists of a sheet 4 of suitable material, having its side edges flanged as shown at 5, and the ends of the strip are cut away from the side flanges 5, so 60 that the said flanges extend at both ends beyond the body of the support, as indicated at 6 and 7 in Fig. 3. One of the ends is beaded as shown at 8, and at each end of the bead a tongue 9 is separated and extends 65 inwardly alongside the adjacent side flange 5, the said tongue being curved upwardly away from the body of the support and thence downwardly as shown at 10 in Fig. 3. At the opposite end of the body, a portion 70 11 of the material of the body is separated from the remainder, and is offset upwardly from the plane of the body, the said portion 11 being connected to the body by means of tongues or strips 12, cut from the material of the body. At each end of the portion 11, a clip 13 is provided, the said clip overlying the upper face of the portion 11.

The frame of the opening through which the pulling tabs extend is shown in Fig. 4, 80 the said frame being formed from a strip of heavy paper or light card-board, having a longitudinal slot 14 at approximately its center and the strip is doubled upon itself longitudinally at the slot. The side edges 85 of the strip are then bent backwardly upon the body to form flanges 15 and 16, and one of the said flanges 16 in the present instance, is seated upon the upper face of the portion 11, the edges of the said flange 16 engaging 90 the clips 13, and the free edge of the flange 15 fits against the inner face of the back of the case 1. The flange 15 as shown in Figs. 7, 9 and 10 is of greater width than the flange 16.

The films 17 are connected with a strip 18 of tough paper of lesser width than the film, and each film is secured upon one face of a sheet 19 of black paper. Each of the sheets 19 is provided with a reduced portion 20, 100 whose free edge is pasted or otherwise secured to the strip 18, and one end of the film is secured to the sheet 19 at its junction with the portion 20.

A plurality of tongues 21 are cut from the sheets 19, five being used in the present instance, and each of the said tongues 21 is pasted or otherwise secured to the one face of the film. Each of the reduced portions 20 is provided with an indicating mark 22, 110 at one side of the end connected with the strip 18, and an arrow 23 is printed on the

said portion adjacent to the indication. Along the said end are printed directions for tearing off the strip. The said directions 24 read "Grasp tab here and tear off".

5 It will be understood that as a rule twelve films are provided in each pack but for the sake of convenience in illustration, only six are shown in the present instance. The mounting however, is alike, and it is not 10 thought necessary to show more.

The portions 20 are connected to the strip 18 in spaced relation and the portions 20 of the sheets 19 are of the same length. The pack is placed in the case after being folded, 15 and to fold the pack the sheets 19 and the films are arranged in superposed relation with the films on the under side and with the portions 20 of the sheets extending outwardly. The strip 18 is then folded between 20 each of the adjacent films as shown at 25 in Figs. 8, 9 and 10. The films and the sheets 19 are placed on one side of the support 4, while the folds 25 of the strip 18 are placed on the opposite side. The films are placed 25 on the opposite side of the support 4 from the tongues 9 and 12, and the connection that is, the portions 20 of the sheets 19 pass around the bead 8, the said bead acting as a roller for reducing friction when the pack 30 is manipulated.

A safety cover 26 of black paper corresponding in all respects to the sheets 19 of the films is placed in front of the uppermost film between the said film and the 35 opening 3 of the case. The safety cover is secured to the strip 18 in precisely the same manner as are the sheets 19, the said safety cover 26 having a reduced portion 27 corresponding to the reduced portions 20 of the 40 sheets 19. The free end of the strip 18 is passed through the slot 14 of the frame for the opening 2, and the free end thereof is cut in triangular form as shown at 28 in Figs. 1 and 2, and the words "Safety cover" are 45 printed on the exposed tab.

The strip 18 is provided with two cuts 29 and 29^a at each fold, the said cuts converging toward their outer ends. The inner end of each cut is spaced apart from the 50 side edge of the strip 18 and their outer ends are spaced apart slightly from each other as shown in Fig. 2. The arrangement is such that by grasping the paper at the point indicated by the inscription 24 and tearing 55 off the projected portion of the strip 18, a tab 30 will be left by means of which the succeeding fold of the strip 18 may be withdrawn to move the exposed film from the front to the rear of the case.

60 In operation, the pack may be sealed in the usual manner by a seal connecting the edge of the opening 3 with the safety cover. If so sealed, the seal must be broken before the pack is placed in the camera. After the 65 pack has been placed in the camera with the

seal broken, the tab 28 is grasped and pulled outward until the indication 22 appears. The first film is now exposed and after the said film has been exposed to light by snapping the camera, the succeeding tab formed 70 by tearing off the projecting portion of the strip 18 may be grasped to move the exposed film to the rear of the case.

It will be understood that as each film is uncovered, the folded portion of the strip 75 18 is torn away.

It will be evident that however many films are used, there will be but one tab exposed at any one time, so that there can be no danger of moving a film before it has 80 been exposed. The case formed from a single sheet of material as specified having side and end flanges, is exceedingly strong, since the side walls and one end wall are doubled.

The tongues 9—10 and the strip 11 of the 85 support hold the films and the backing sheets at the front of the case and the flanges 5 guide the strip in its movement. It will be noted from an inspection of Fig. 8 that the said strip is inside the tongues 9—10 and 12. 90

It will be noted that three of the tongues 21 are secured to the face of the film intermediate the side edges thereof, while the other two, that is, the outermost ones are secured to the corners of the film. The outermost tongues hold the films at the corners, 95 and prevent the film catching as it is moved in the pack.

It will be noted also that a strip 31 of plush is secured to the bottom of the case 100 and a similar strip 32 is secured to the frame at the opening 14. The said strips 31 and 32 are for the purpose of shutting out light and reducing friction. The black backing sheets are glossy on their rear face 105 to reduce friction and in the present instance the gloss is produced by a gum solution, which may be used to cement the tongues to the film and to cement the extension to the strips 18.

Instead of using a seal to seal the pack, the tab 28 shown in Fig. 1 may be sealed to the safety cover as shown in the said figure. When so arranged a separate seal is unnecessary and there is no possibility of loading 115 the camera with a sealed pack.

The particular arrangement of the tongues 21 prevents any catching of the end of the film as it is drawn to the rear of the case. The utilization of the first tab for a 120 seal absolutely prevents the failure to break the seal, since the safety cover cannot be withdrawn until the tab is released.

The employment of a single piece of card board or paper in the formation of the case 125 provides a double thickness of material at each edge and at one end, thus making a very strong and rigid construction with a minimum of paper or card board.

It will be noticed that the spur or lug 33 130

is struck up from the metal support at the end adjacent to the portion 11 of the said support and at the center of the said end of the support, the said spur extending in the 5 opposite direction to the said portion. The spur or lug is pointed and passes through the ends of the backing sheets as shown in Fig. 9. When the folded strip with the films is placed on the support, the free ends 10 of the backing sheets are pressed toward the support in such manner that the spur passes through the said free ends. The spur holds the loose ends of the backing sheets in place and prevents any possibility of moving 15 more than one film at a time. The sheets are easily removed singly however, the spur tearing out as the films are withdrawn.

In folding the paper or card board forming the case, the inside end flange 34 is provided with three or more spots of adhesive 20 and that portion of the strip forming the top of the case is creased transversely at approximately the center of the case as shown at 35 and the side flanges are clipped transversely at the crease. When now it is desired to open the case, the flange 34 is separated from the outer flange 36 and that portion of the top of the case between the line 35 and the flap 34 may be turned up as 30 shown in Fig. 7 in the shape of a cover, to permit the removal of a portion or all of the contents of the case.

I claim:

1. A film pack comprising a case having 35 an opening in its front and a slot in one end, a rigid support within the case, a plurality of films, a sheet of black paper for each film, each sheet having a reduced extension at one end and each film having one 40 end secured to a sheet at the junction of the sheet with the extension, a strip of paper to which the extensions are secured at their free ends transversely of the strip and in spaced relation, the films and the sheets being arranged on the front of the support behind the opening of the case and each film in front of its sheet, the said strip being folded between the attachment of the adjacent extensions, said folds being on the 45 opposite side of the support from the films, the support being beaded at the end where the extensions pass around the same and having resilient tongues at each side at the said end for pressing the films toward the 50 opening and having a lateral extension at the opposite end for pressing the films toward the opening, the folds of the strip being of such length that when unfolded, a film and its sheet will be drawn from the 55 front to the rear of the support, the free end of the strip being beveled and extending through the slot at the end of the case, said strip being partially separated adjacent to the connection of each extension therewith by two cuts converging 60 to the center of the strip.

their outer ends to form a tab when the extended fold has been torn away, and a safety cover for the outermost film having a reduced extension connected to the strip at the end remote from the tab.

2. A film pack comprising a case having an opening in its front and a slot in one end, a rigid support within the case, a plurality of films, a sheet of black paper for each film, each sheet having a reduced extension at one end and each film having one 70 end secured to a sheet at the junction of the sheet with the extension, a strip of paper to which the extensions are secured at their free ends transversely of the strip and in spaced relation, the films and the sheets being arranged on the front of the support behind the opening of the case with each film in front of its sheet, the said strip being folded between the attachments of the adjacent extensions, said folds being on the opposite side of the support from the films, the folds of the strip being of such length that when unfolded a film and its sheet will be drawn from the front to the rear of the 75 support, the free end of the strip being beveled and extending through the slot at the end of the case, said strip being partially separated adjacent to the connection of each extension therewith by two cuts converging toward their outer ends to form a tab when the extended fold has been torn away, and a safety cover for the outermost film having a reduced extension connected to the strip at the end remote from the tab.

3. A film pack comprising a case having an opening in its front and a slot in one end, a rigid support within the case, a plurality of films, a sheet of black paper for each film, each sheet having a reduced extension at one end and each film having one 80 end secured to a sheet at the junction of the sheet with the extension, a strip of paper to which the extensions are secured at their free ends transversely of the strip and in spaced relation, the films and the sheets being arranged on the front of the support behind the opening of the case with each film in front of its sheet, the said strip being folded between the attachments of the adjacent extensions, said folds being on the opposite side of the support from the film, the folds of the strip being of such length that when unfolded a film and its sheet will be drawn from the front to the rear of the 85 support, the free end of the strip being beveled and extending through the slot at the end of the case, said strip being partially separated adjacent to the connection of each extension therewith by two cuts converging toward their outer ends to form a tab when the extended fold has been torn away, and a safety cover for the outermost film having a reduced extension connected to the strip at the end remote from the tab.

4. A film pack comprising a case having an opening in its front and a slot in one end, a rigid support within the case, a plurality of films, a sheet of black paper for each film, each sheet having a reduced extension at one end and each film having one 90 end secured to a sheet at the junction of the sheet with the extension, a strip of paper to which the extensions are secured at their free ends transversely of the strip and in spaced relation, the films and the sheets being arranged on the front of the support behind the opening of the case with each film in front of its sheet, the said strip being folded between the attachments of the adjacent extensions, said fold being on the opposite side of the support from the film, the folds of the strip being of such length that when unfolded a film and its sheet will be drawn from the front to the rear of the 95 support, the free end of the strip being beveled and extending through the slot at the end of the case, said strip being partially separated adjacent to the connection of each extension therewith, the free end of the strip being cut away to form a tab and extending through the slot, said strip being partially separated adjacent to the connection of each extension to form a tab when the extended fold has been torn away, and

- 4
- a safety cover for the outermost film connected with the strip and movable with the strip away from in front of the film when the first fold of the strip is unfolded.
- 5 4. A film pack comprising a case having an opening in its front and a slot in one end, a plurality of films, a backing sheet for each film connected to the film at one end, a moving strip for the films, the extensions 10 of the backing sheets being connected to the moving strip at spaced intervals and the said strip being folded between the said connections in such manner that when a fold is unfolded, a film will be drawn from 15 the front to the rear of the case, the free end of the strip having a tab extending through the slot, said strip being partially separated adjacent to each extension to form a pulling tab when the unfolded fold has been torn 20 away, a safety cover for the outermost film connected to the strip, and a support in the case, the films and backing sheets being in front of the support and the folds of the strip in rear of the support.
- 25 5. In a film pack, the combination with the films and the backing sheets therefor, each film being connected to its backing sheet at one end and each sheet having a reduced extension at the said end, a moving 30 strip for the films of approximately the width of the extensions, the extensions being connected to the strip in spaced relation and said strip being folded between the said 35 connections in such manner that when a fold is unfolded a film and its backing sheet will be moved from the front to the rear of the case, said strip having a reduced tab at its outer end and being partially separated near the junction of each extension there- 40 with in such manner that when the fold of the strip is torn away, a tab will be left for unfolding the next fold.
6. In a film pack, the combination with the films and the backing sheets therefor, 45 each film being connected to its backing sheet at one end and each sheet having a reduced extension at the said end, a moving strip for the films, the extensions being connected to the strip in spaced relation and 50 said strip being folded, said strip having a pulling tab at its free end and being partially separated adjacent to the connection of each extension in such manner that when an unfolded fold is torn away from the strip 55 a pulling tab for the next film will remain.
7. In a film pack, a support of rigid material having its side edges flanged laterally rearward to limit the lateral movement of the films, each of the said flanges extending 60 beyond the support at each end, the inner end of the said support being beaded and having adjacent to each flange an integral tongue, the opposite end of the support being separated from the support and connected thereto by integral resilient tongues 65 cut from the support, the said end being offset laterally rearward, said end having a clip adjacent to each flange, and a guiding frame for the pulling strip composed of a strip of material folded longitudinally upon 70 itself and having a slot at the fold, the free edges of the strip being flanged laterally, one of the said edges being adapted to engage the clips of the support, and the other the back of the case. 75
8. In a film pack a support of rigid material having its side edges flanged laterally rearward to limit the lateral movement of the films, each of the said flanges extending beyond the support at each end, the inner end of the said support being beaded and having adjacent to each flange an integral tongue, the opposite end of the support being separated from the support and connected thereto by integral resilient tongues 80 cut from the support, the said end being offset laterally rearward, said end having a clip adjacent to each flange. 85
9. In a film pack, a support of rigid material having its side edges flanged laterally rearward to limit the lateral movement of the films, each of the said flanges extending beyond the support at each end, the inner end of the said support being beaded and having adjacent to each flange an integral tongue, the opposite end of the support being separated from the support and connected thereto by integral resilient tongues 90 cut from the support, the said end being offset laterally rearward. 95
10. In a film pack, a support consisting of a sheet of metal having a lateral rearwardly extending flange at each side edge and having a bead at its inner end and an integral rearwardly extending spring tongue 105 at the said end adjacent to each flange, a portion of the sheet at the opposite end being separated and connected to the sheet by resilient integral tongues, the said separated end being offset laterally rearward. 110
11. In a film pack, the combination with the film and the backing sheets therefor, each film being connected to its backing sheet having a reduced extension at the said end and a moving strip for the film, said extensions being connected to one face of the strip in transverse spaced relation. 115
